US00D593412S

(12) **United States Design Patent**
Gonzalez et al.

(10) **Patent No.:** **US D593,412 S**
(45) **Date of Patent:** **** Jun. 2, 2009**

(54) **PART OF AN AEROSOL**

(75) Inventors: **Daniel Omar Gonzalez**, Buenos Aires (AR); **Diego Iglesias**, Ciudad de Buenos Aires (AR); **Javier Eduardo Mateu**, Buenos Aires (AR); **Martin Gabriel Urtubey**, Ciudad de Buenos Aires (AR)

(73) Assignee: **Conopco, Inc.**, Englewood Cliffs, NJ (US)

(**) Term: **14 Years**

(21) Appl. No.: **29/286,411**

(22) Filed: **May 4, 2007**

(51) **LOC (9) Cl.** **09-01**

(52) **U.S. Cl.** **D9/516; D9/537**

(58) **Field of Classification Search** **D9/516, D9/529, 530, 537, 540, 549, 551, 552, 553, D9/556, 557, 558, 564, 565, 566, 569, 570, D9/571, 575; 215/381-385, 396, 398**

See application file for complete search history.

(57) **CLAIM**

The ornamental design for a part of an aerosol, as shown and described.

DESCRIPTION

FIG. 1 is front perspective view of a part of an aerosol showing our new design;

FIG. 2 is a rear elevation view thereof;

FIG. 3 is a side elevational view thereof;

FIG. 4 is a top plan view thereof; and,

FIG. 5 is a bottom plan view thereof.

The broken line showing of a part of an aerosol is included for the purpose of illustrating only and forms no part of the claimed design.
